(57) **CLAIM**

The ornamental design for LED housing as shown and described.

DESCRIPTION

FIG. 1 is a front three-dimensional view of the LED housing;

FIG. 2 is a front elevational view of the LED housing;

FIG. 3 is a rear elevational view of the LED housing;

FIG. 4 is a left side elevational view of the LED housing;

FIG. 5 is a right side elevational view of the LED housing;

FIG. 6 is a top plan view of the LED housing; and,

FIG. 7 is a bottom plan view of the LED housing.

The broken lines depict portions of the LED housing in which the design is embodied and form no part of the claimed design.
